ABSTRACT OF THE DISCLOSURE

The present invention describes 3,4-dihydroxybenzoxazinones of the formula:

I

wherein R₁, R₂, R₃, and R₄ are described below.

These compounds are useful as anti-inflammatory agents.

This invention relates to compositions of matter. More particularly, this invention relates to new and novel 3,4-dihydroxybenzoxazinones and process for their production.

The new and novel 3,4-dihydroxybenzoxazines may be represented by the formula:

I

wherein R₁ may be straight or branched chain lower alkyl of 1 to 6 carbon atoms; lower alkenyl such as alkyl, methylallyl, dimethylallyl; cycloalkyl such as cyclopropyl, cyclopropylmethyl, cyclopentyl, cyclohexyl, and the like; R₂ may be

in which R₇ has the same significance as

is which R₈ may be lower alkyl of 1 to 6 carbon atoms, lower alkoxy of 1 to 6 carbon atoms, halogen, nitrogen, and the like; imides such as

heterocyclics such as

2

and the like; malonic esters such as

β -keto esters such as

aliphatic, aryl or aralkyl 1,3-diketones such as

cycloaliphatic 1,3-diketones such as

in which n is from 1 to 4; 1,3-cyclohexanedione, 1,3-cyclopentanedione, cycloaliphatic ketones such as

cyclopentanone, cyclohexanone, cycloheptanone and methylcyclohexanone; aliphatic ketone such as

2-butanone, 2-pentanone, 2-hexanone and the like; aliphatic halo ketones such as

β -ketonitriles,

aryl ketones such as

aralkyl ketones such as

substituted phenols such as lower alkyl substituted phenols, nitro or halo substituted phenols and the like; aliphatic 1,2-diketones such as

and cycloaliphatic 1,2-diketones such as 1,2-cyclohexanedione, 1,2-cyclopentanedione, 1,2-cycloheptanedione, 1,2-

cyclooctanedione and the like; R_3 and R_4 each may be hydrogen, halogen such as chlorine, bromine, iodine and fluorine, straight or branched chain lower alkoxy of 1 to 6 carbon atoms, straight or branched chain lower alkyls of 1 to 6 carbons, carbamylloxy such as

in which R_6 has the same significance as R_1 and nitro.

The symbols R_1 , R_2 , R_3 , R_4 , R_5 , R_6 , R_7 and R_8 used hereinafter have the same meaning as defined above. 10

Exemplary of the compounds of this invention are tabulated below:

The compounds of this invention are useful as anti-inflammatory agents. For example, in a test for determination of anti-inflammatory activity in warm-blooded mammals such as mice employing a procedure described by O'Driscoll et al., Canadian Journal of Physiology and Pharmacology, volume 42 (1964), it was found that some of the compounds are capable of suppressing lung inflammation in albino mice to a marked degree and in some instances to an extent estimated to be up to 55.2% over untreated mice. Accordingly, these compounds are useful in treating the inflammatory process either systemically or locally. In use, the compounds of this invention are combined with an inert pharmaceutical diluent to form

dosage forms such as tablets, capsules, elixirs, suspensions, suppositories, parentals and the like with the active ingredient being present in an amount from 1 mg. to 1000 mg. per dosage unit. The compounds of this invention may also be combined with other known therapeutic agents, for example, steroids such as β -methasone, β -methasone-17-valerate, prednisolone, cortisone and the like, analgesics such as aspirin, tranquilizers such as the 1,4-benzodiazepines, antibiotics such as neomycin, colymycin, anti-histamines such as chlorpheniramine and the like to enhance and broaden their therapeutic spectrum. The compounds of this invention are useful as intermediates for the production of other novel compounds as exemplified by the following reactions.

(1) Treatment with NaOR₁

Treatment of compounds exemplified by Formula I with sodium hydroxide in an alcohol such as methanol causes ring opening to give compounds of type V:

(2) Reduction

Compounds having a ketone group may be reduced to alcohols by sodium borohydride to give compounds of type VI:

In turn compounds of type VI may be converted by reaction 1 to compounds of type V.

(3) Conversion to other heterocycles

Compounds having 1,2 and 1,3-dicarbonyl groups may be converted to other heterocycles, for example:

These compounds will form the basis of further applications.

According to the process of this invention, the compounds are prepared by reacting compounds of the Formula II:

with any compound having an active hydrogen atom. Thus, they are reacted with a compound of the formula R₂H wherein said active hydrogen is attached to the bond of, for example, NH₂COOR₂, or H₂NSO₂O₆H₅. The reaction is conducted in an inert solvent such as benzene, toluene, chloroform or tetrahydrofuran in the presence of an acidic catalyst such as p-toluene sulfonic acid; the reaction is effected by heating together the reactants in a suitable vessel. It is preferable, in some instances, to include in the reaction vessel provision for effecting simultaneous azeotropic distillation of the solvent to remove the water formed thereby expediting the completion of the reaction. A suitable device for water removal is a Dean-Stark trap. The desired reaction products are recovered by simply evaporating the reaction mixture to dryness and recrystallizing the product from a suitable solvent such as ethyl acetate, methanol, ethanol, cyclohexane and the like.

The starting materials used in the above reaction are prepared in accordance with directions given by R. E. Strube et al., Recueil 83 No. 9-10, p. 1191 (1964).

It has also been found that in carrying out this reaction, Compound II itself reacts to form compounds of the Formula III:

Compounds corresponding to III are not within the scope of this invention but will form the basis of a further application.

In order to further illustrate the invention, the following examples are given. All temperatures are given in degrees centigrade and room temperature is at 20 to 30° C.

EXAMPLE 1

4-benzenesulfonamido-3,4-dihydro-3-methyl-2H-1,3-benzoxazin-2-one

A solution of 6.0 g. of 3,4-dihydro-4-hydroxy-3-methyl-2H-1,3-benzoxazin-2-one and 5.25 g. of benzene-sulfonamide in 300 ml. of anhydrous benzene is refluxed for two hours, whereas 0.60 ml. water is collected in a Dean-Stark trap. After cooling, the white crystals are filtered off to give 9.2 g. of 4-benzenesulfonamido-3,4-dihydro-3-methyl-2H-1,3-benzoxazin-2-one, M.P. 201-203°. Concentration of the filtrate to about 15 ml. and cooling gives an additional crop of 1.1 g. of white crystals, M.P. 201-203°; yield 97%. Recrystallization from ethyl

acetate gives analytically pure, white crystals, M.P. 203-204.5°;
